UNITED STATES PATENT OFFICE.

EDWIN L. PAGE, OF KINGSLEY, IOWA.

VENTILATED BLOCK.

1,404,161.

Specification of Letters Patent. Patented Jan. 17, 1922.

Application filed May 16, 1921. Serial No. 469,916.

To all whom it may concern:

Be it known that I, EDWIN L. PAGE, a citizen of the United States, and a resident of Kingsley, in the county of Plymouth and 5 State of Iowa, have invented a certain new and useful Ventilated Block, of which the following is a specification.

The object of my invention is to provide a 10 ventilated building block especially adapted to be used in constructing corn cribs and buildings of that general type, the block being comparatively cheap and very durable.

More particularly my invention relates to 15 that type of block made with the use of my core for making ventilated blocks, which is made the subject matter of my co-pending application, Serial Number 468,473, filed May 11, 1921.

Still another object is to provide a building block of greater length than width and 20 adapted to have a pair of openings formed therein, each of the openings being provided with a plurality of blades so positioned that passageways will be had for air, but it will 25 be impossible for rain to pass through said openings.

Still another object is to provide the blades 30 with inclined portions, the upper edge of one horizontal plane as the lower edge of the adjacent blade; parts of the blades being embedded in the material from which the block is made for holding the blades in position.

Still another object is to arrange the ends 35 of the blades so that when they are received in the plastic material from which the block is made they will lie in a plane substantially parallel to the top and bottom of the block.

Still another object is to provide grooves 40 on the sides of the opening and opening into the inner side of the block so that new blades may be slipped into the block if necessary.

With these and other objects in view my 45 invention consists in the construction, arrangement and combination of the various parts of my device, whereby the objects contemplated are attained, as hereinafter more fully set forth, pointed out in my claims, 50 and illustrated in the accompanying drawings, in which:

Figure 1 is a perspective view of one of my ventilated blocks.

Figure 2 is a sectional view taken on the 55 line 2-2 of Figure 1.

Figure 3 is a side elevation of one of the blades which form the ventilated portion of the block.

Figure 4 is an end elevation of the blade; 60 and

Figure 5 is a sectional view through one of the blades showing a modified form of anchoring the blades to the block material.

In the accompanying drawings I have used the reference numeral 10 to indicate 65 generally a block of greater length than width. The block 10 being provided with concave and convex side edges so that when the block is stood on end the abutting edges of the adjacent blocks will co-act with each 70 other.

The block 10 is provided with a pair of 75 openings 11. The openings 11 are provided with a plurality of blades 12. Each of the blades 12 comprise a body portion which is inclined relative to the top and bottom of the block.

Each of the blades 12 are provided with 80 ends 13 which are bent relative to the main body portion of the blade so that it rests in a substantial horizontal plane when in position.

The ends 13 are of less width than the 85 blade 12. The ends 13 of the blade are permitted to set in the material from which the block is made for thus positioning the blades in the block.

When the blocks are originally made 90 grooves 14 are provided which are of substantially the same length as the ends 13 of the blades, and substantially the same width. The purpose of the grooves 14 will now be mentioned.

It may be stated that some times the 95 blades become broken and it is desirable to replace them. The old blades may be removed from the blocks and a new blade may then be slipped into place.

It will be understood that the blades are placed in the block when originally made 100 and the ends 13 are permitted to set, which will prevent the possibility of the blades from slipping out from the block.

But when a new blade has been inserted 105 the groove may be plugged up for preventing the blade from sliding out.

In Figure 5 of the drawings I have shown the ends of the blades received in the block, but no grooves for the inserting of new blades. It may be mentioned that this type 110

of block will be ordinarily used, as new blades are only required in exceptional instances.

It will be seen that I have provided a very efficient building block which will prove very efficient for ventilation, and yet be rain proof.

Some changes may be made in the construction and arrangement of the parts of 10 my block without departing from the real spirit and purpose of my invention, and it is my intention to cover by my claims, any modified forms of structure by the use of mechanical equivalents, which may be reasonably included within their scope.

I claim as my invention:

1. A ventilated building block having a pair of openings therein arranged lengthwise of the block, each of said openings 20 being provided with a plurality of inclined blades having their ends embedded in the block for holding them in position, the ends of said blades being arranged parallel with the top and bottom of the block.

2. A ventilated building block having a pair of openings therein arranged lengthwise of the block, each of said openings being provided with a plurality of inclined blades having their ends embedded in the 30 block for holding them in position, the upper edge of one blade lying in substantially the same horizontal plane as the lower edge of the adjacent blade, the ends of said blades being arranged parallel with the top and bottom of the block.

3. A ventilated building block of greater length than width provided with a pair of openings arranged lengthwise of the block, each of said openings having a plurality of 40 blades therein, the ends of said blades being of less width than the main body portion of the blades and embedded in the block, the exposed portion of the blades being upwardly inclined from front to rear so as to 45 serve as a drain, the upper edge of one blade being in substantially the same horizontal plane as the lower edge of the adjacent blade, the ends of the blades being substantially parallel with the top and bottom of the block.

4. A ventilated building block having a pair of openings therein arranged lengthwise of the block, each of said openings being provided with a plurality of inclined 55 blades having their ends embedded in the block for holding them in position, the upper edge of one blade lying in substantially the same horizontal plane as the lower edge of

the adjacent blade, the ends of said blades being arranged parallel with the top and bottom of the block, the sides of said openings being provided with registering grooves so that blades may be slipped into or out of position as desired.

5. A ventilated building block rectangular 60 in outline and of greater length than width, and provided with an opening arranged lengthwise of the block, said opening having a plurality of blades therein, the ends of said blades being of less width than the 70 main body portion of the blades and embedded in the block, the exposed portion of the blades being upwardly inclined from front to rear so as to serve as a drain, the upper edge of one blade being in substantially the same horizontal plane as the lower edge of the adjacent blade, the ends of the blades being substantially parallel with the top and bottom of the block.

6. A ventilated building block of greater 75 length than width provided with a pair of openings arranged lengthwise of the block, blades received within each of said openings, said blades being of greater length than the width of said openings so that the ends 85 thereof may be embedded in the block, the portion of the blade received within the opening being substantially wider than the portions received within the block, said first portion of the blades being inclined upwardly from front to rear so as to serve as a drain, the blades being so positioned that the upper edge of one blade lies in substantially the same horizontal plane as the lower edge of the adjacent blade, the portions of the blades embedded in the block are 90 so arranged that they are substantially parallel with the top and bottom of the block.

7. A ventilated building block having an 100 opening therein arranged lengthwise of the block, said opening being provided with a plurality of blades having their ends embedded in the block for holding them in position, the ends of said blades being arranged 105 parallel with the top and bottom of the block.

8. A ventilated building block having a pair of openings therein arranged lengthwise of the block, each of said openings 110 being provided with a plurality of blades having their ends embedded in the block for holding them in position, the ends of said blades being arranged parallel with the top and bottom of the block.

EDWIN L. PAGE.
